UNITED STATES PATENT OFFICE.

ALBERT J. D. OHM, OF NEW YORK, N. Y., ASSIGNEE TO INCANDESCENT SUPPLY COMPANY, A CORPORATION OF NEW YORK.

DESIGN FOR A LIGHTING-FIXTURE BAND.

Application filed July 25, 1924. Serial No. 10,257. Term of patent 3½ years.

To all whom it may concern:

Be it known that I, ALBERT J. D. OHM, a citizen of the United States, and residing at New York city, in the county of Queens and State of New York, have invented a new, original, and ornamental Design for Lighting Fixture Band, of which the following is a specification, reference being had to the accompanying drawings, forming part hereof.

The figures of the drawing show the design of the article. Fig. 1 is a side view of the lighting fixture band.

Fig. 2 is a bottom view of the lighting fixture band showing a portion with the design filled in.

I claim:

The ornamental design for a lighting fixture band, as shown.

ALBERT J. D. OHM.
